UNITED STATES PATENT OFFICE.

JAMES E. DAVIDSON, OF PITTSBURG, PENNSYLVANIA.

PLACKET-CLOSER, &c.

SPECIFICATION forming part of Letters Patent No. 630,190, dated August 1, 1899.

Application filed November 11, 1898. Serial No. 696,132. (No model.)

To all whom it may concern:

Be it known that I, JAMES E. DAVIDSON, a citizen of the United States of America, residing at Pittsburg, in the county of Allegheny and State of Pennsylvania, have invented certain new and useful Improvements in Vent-Closing and Skirt-Supporting Devices, of which the following is a specification, reference being had therein to the accompanying drawings.

This invention relates to certain new and useful improvements in skirt-supporters and may be more particularly defined as a combination skirt-supporter and placket-closer.

The object of this invention is to provide new and novel means whereby a skirt may be easily supported or suspended from the belt and to provide further means whereby the placket or slit in the skirt may be conveniently and effectively closed and an accidental displacement or opening of the placket prevented.

The invention has for its further object to construct a device of the above-referred-to class that will be extremely simple in construction, strong, durable, and comparatively inexpensive to manufacture.

A still further object of the invention is to construct a device that may be easily applied to and removed from the garment when desired and, furthermore, one that may be easily opened and closed.

With the above and other objects in view the invention finally consists in the novel construction, combination, and arrangement of parts to be hereinafter more fully described, and particularly pointed out in the claim.

In describing the invention in detail reference is had to the accompanying drawings, forming a part of this specification, and wherein like figures of reference indicate like parts throughout the several views thereof, and in which—

Figure 1 represents a skirt and belt provided with my improved supporter and placket-closer. Fig. 2 represents a plan view of my improved supporter and placket-closer. Fig. 3 represents a side view of the same. Fig. 4 represents a perspective view of the same. Fig. 5 represents an enlarged view of a portion of one of the sections of the device, showing more particularly a form of fasten-

ing means. Fig. 6 is a similar view showing a modified form of fastening means. Fig. 7 is a detail view, partly in section, showing a modified form of locking means.

In the drawings, 1 indicates the main section of my improved skirt-supporter and placket-closer, said section having formed at its upper free end a hook 2 and provided at its lower extremity with an aperture 3. Said lower extremity is slightly bent downward, as shown at 4, to form a shoulder.

The numeral 6 represents the socket, which is adapted to receive the head 7, formed on the face of the section 8. Said section is likewise provided with an aperture at its lower extremity, which aperture corresponds with the aperture 3 formed in the section 1, both apertures being adapted to receive a rivet 9, forming a pivotal connection between the sections 1 and 8. The said section 8 is likewise provided with a shoulder 10, corresponding with the shoulder 4 of the section 1.

The numeral 11 indicates barbs formed integral with the sections 1 and 8, which serve to fasten the sections to the fabric.

The numeral 12 designates an aperture formed in the sections 1 and 8, which may serve to stitch the sections to the garment.

In actual practice I find it advantageous to dispense with the fastening means as shown in Figs. 5 and 6 of the drawings, but prefer to hem the sections 1 and 8 to the edges of the slit or placket.

The operation of this device will be readily apparent from the above description. The sections 1 and 8 are placed on opposite sides of the hem of the edges of the skirt, forming the slit, the hook 2 engages the upper edge of the belt when the garment is placed in position, and the two sections 1 and 8 are brought together and by a slight pressure the head 7 engages the shank 6 and the sections are securely locked together. The shoulders 4 and 10 serve to form a space between the sections 1 and 8 (see Fig. 3) of sufficient width to compensate for the thickness of the fabric, thus allowing both sections to be easily operated. In order to open the slit and remove the garment, only a slight pressure is required to disengage the head 7 from the shank portion 6, and the sections may be then operated, as shown in dotted lines in Fig. 2 of the drawings.

It will be noted that various changes may be made in the details of construction of my improved skirt-supporter and placket-closer without departing from the general spirit of 5 my invention.

Having thus fully described my invention, what I claim as new, and desire to secure by Letters Patent, is—

A skirt-supporter and placket-closer consisting of two elongated sections of unequal length pivotally connected at one end, each of said sections being bent outwardly near the pivoted end to separate the sections, the longer of said sections having a hook formed

integral with its free end adapted to engage 15 a belt, a button secured to the inner face of the shorter section near its free end, the longer of said sections having a socket arranged in registering position with said button to receive the same, and securing means carried by 20 each of said sections for engaging the skirt substantially as herein shown and described.

In testimony whereof I affix my signature in the presence of two witnesses.

JAMES E. DAVIDSON.
